(57) **CLAIM**

The ornamental design for a tablet computer, as shown and described.

DESCRIPTION

FIG. 1 is a front elevation view of a tablet computer showing the new design;
 FIG. 2 is a rear elevation view thereof;
 FIG. 3 is a left side elevation view thereof;
 FIG. 4 is a right side elevation view thereof;
 FIG. 5 is a top plan view thereof;
 FIG. 6 is a bottom plan view thereof;
 FIG. 7 is a rear isometric view thereof;
 FIG. 8 is a front elevation view thereof with the stand being in an open position;
 FIG. 9 is a rear elevation view thereof;
 FIG. 10 is a left side elevation view thereof;
 FIG. 11 is a right side elevation view thereof;
 FIG. 12 is a top plan view thereof;
 FIG. 13 is a bottom plan view thereof; and,
 FIG. 14 is a rear isometric view thereof.
